UNITED STATES PATENT OFFICE.

AARON J. KLINE AND LUCIUS N. MUIR, OF JERSEY SHORE, PENNSYLVANIA.

IMPROVED WASHING-MACHINE.

Specification forming part of Letters Patent No. 35,385, dated May 27, 1862.

To all whom it may concern:

Be it known that we, AARON J. KLINE and LUCIUS N. MUIR, of Jersey Shore, in the county of Lycoming and State of Pennsylvania, have invented a new and useful Improvement in Washing-Machines; and we do hereby declare that the following is a full, clear, and exact description of the construction and operation of the same, reference being had to the accompanying drawings, making a part of this specification, in which—

Figure 1 is an end view or elevation; Fig. 2, a longitudinal vertical section as indicated by the line 1 2 in Fig. 1.

Like letters in both figures designate corresponding parts, and parts that are not seen are shown in dotted lines.

The nature of our improvement is in the construction of the machinery by which the operation of washing is performed with comparative ease and dispatch, requiring but little exertion, and doing the work of washing in as effectual and thorough a manner as possible. To accomplish this we construct and use a double cranked iron shaft passing transversely through double-slotted arms suspended from a head or cross-piece fitted sufficiently loose to move up and down in slotted stationary uprights screwed onto the outsides of the box, and which support the shaft, the cranks on the shaft necessarily producing an easy and rapid rocking motion to the washing-board, which is joined to the slotted arms, whenever motion is given to the crank-handle on the end of the shaft.

In the regulation of the pressure of the washing-board upon the clothes to be washed, while one hand is engaged on the crank-handle the other is applied to a handle-rod at the end of the box, projecting sufficiently above the top to be conveniently taken hold of, extending down and secured to a spring-lever which extends the entire diagonal length, and fastened at one end underneath the box by a hinge or hook. Two sliding bars, the top ends of which are connected to the head or cross-piece in the slotted uprights extending down below the box, are connected to the spring-lever by means of a rod linked or held to it by a hook or staple in the center, passing transversely

through them, and secured at the ends by nut-screws. The turning of the crank-handle with one hand and the application of the other to the pressure-rod may be done simultaneously, at the discretion of the operator, with facility and ease.

In order to enable any one skilled in the art to make and use our invention, we will proceed to describe its construction in detail.

A is the washing-box, of a longitudinal form, resting on legs I.

D is a double-cranked iron shaft supported immediately above the top of the box in notched openings in the sides of the slotted uprights E, which are screwed onto the outsides of the box about midway, and projecting sufficiently above the top of the box support the head or cross-piece H in slots near the top of each, to which is suspended the slotted arms C and washing-board. The cranks on the shaft passing through operate in each of the slots.

F are sliding bars placed on the outside of the box alongside of and flush with the outside faces of the slotted uprights E, being kept in their places by cleats d. The tops are connected to the head or cross-piece H by small brass or iron plates screwed on the insides and cut out to receive it.

G is a spring-lever secured at one end underneath the box by a hinge or hook of some kind. At the other end is a handle-rod, b, projecting upward on the outside end of the box, and which is kept steady by two hooks or staples being driven in. About midway and underneath the spring-lever G is a transverse rod, c, secured at each end to the sliding bars F, which project down sufficiently below the box, by nut-screws.

B is a permanent washing-board about midway of the box, having a series of revolving rollers, every other one being stationary. Around the slots on the inside of each of the arms C, or both sides, if deemed necessary, are thin brass or iron plates e, screwed on to protect the wood from the friction occasioned by the revolution of the shaft D.

The double-cranked shaft D may be entirely removed from the openings in the slotted uprights E by raising two small movable brass

catches, *f*, which are screwed on to keep it in place, being slipped through the slotted arms *C*.

What we claim as our invention, and desire to secure by Letters Patent, is—

The arrangement and combination of the double cranked shaft *D*, double-slotted arms *C*, double sliding bars *F*, double-slotted uprights *E*, head or cross-piece *H*, and spring-

lever *G*, the whole constructed and operated in the manner herein described and set forth.

AARON J. KLINE.

LUCIUS N. MUIR.
